INCUBATOR CONSTRUCTION

Albert V. Rackstraw, Gardena, Calif.

Application April 23, 1930. Serial No. 446,556

4 Claims. (Cl. 119—37)

This invention relates to the construction of cabinet type electric incubators.

An object of the invention is to provide an incubator construction wherein the ventilation 5 will be secured in a more uniform and dependable manner.

Another object of the invention is to provide improved means for producing a stabilized properly heated air current which will be circulated 10 through the egg trays of the incubator in such a manner as to produce a dependable even heat of the required temperature. This object is carried out by means of an improved construction and arrangement of partitions within the 15 casing and a novel arrangement of air flues to distribute the air in an improved manner after it passes through the fan or blower which is provided to keep the air in circulation and to secure a proper ventilation within the incubator. 20 Still another object of the invention is to provide for assembling a plurality of cooperating incubator units in an improved manner so that the fans or blowers which circulate the air within each incubator unit may all be driven 25 by a single motor; and the incubator units are joined to each other in such a manner that heat radiation through the walls of the casing of each unit is reduced and the cost of keeping the temperature of each unit up to the required amount 30 is thereby lessened.

Other objects are to, in general, improve upon and simplify the internal construction of the incubator.

Still other objects, advantages and features of 35 invention may hereinafter appear.

Referring to the accompanying drawings which illustrate what is at present deemed to be a preferred embodiment of the invention,

Fig. 1 is a front end elevation of one of the 40 incubator units including also a fragment of an adjacent cooperating incubator unit.

Fig. 2 is a side elevation of one of the incubator units.

Fig. 3 is a plan view of one of the incubator 45 units.

Fig. 4 is a transverse section on line 4—4 of Fig. 1.

Fig. 5 is a fragmental side elevation of parts 50 of the lower water pan and air circulating device.

Fig. 6 is a transverse section on line 6—6 of Fig. 1.

Fig. 7 is a vertical section on irregular line 7—7 of Fig. 3.

Fig. 8 is a vertical section on line 8—8 of 55 Fig. 3.

Fig. 9 is a vertical section on irregular line 9—9 of Fig. 3.

Fig. 10 is a fragmental transverse section on line 10—10 of Fig. 1.

Fig. 11 is a fragmental sectional view on line 11—11 of Fig. 8.

Referring in detail to the drawings, each incubator unit 7 is preferably formed as a rectangular compartment having side walls 9 the rear end wall 10 and a front end wall 11, the latter wall being provided with a door 12 which affords access to the interior of that incubator unit.

Within each incubator unit in spaced relation to each of its side walls 9 is mounted a vertical partition 15 which extends from end to end of the incubator unit but which does not extend all the way to either the top or bottom of the chamber of such incubator unit.

To the inner face of each partition 15 is secured a series of horizontal vertically spaced cleats 17 upon which rest the incubator trays 18. Said incubator trays 18 are of the open mesh or screen type in order to permit the air to circulate freely through their bottom portions.

Below this series of trays 18 is located an upper water pan 20 and a lower water pan 21, these water pans being placed one above the other in spaced relation to each other. The upper water pan 20 is supported by the lowest pair of cleats designated 17a, said water pan extending from end to end of the cabinet but having each of its long sides spaced away from the adjacent side of the cabinet in order to provide an air space 25 at that place. The lower water pan 21 is much smaller than the upper water pan 20 and is positioned at the mid-width of the cabinet floor with its long sides parallel to the end walls of the cabinet. The length of said water pan 21 is somewhat less than the width of the cabinet 90 chamber and an equal space is provided between each end of this water pan and the adjacent side of the cabinet. The upper water pan 20 is located immediately above a restricted air space 95 which intervenes between the same and the blower 37.

A well known type of electrical resistance heater bars 30 are supported in a cross-wise manner upon the opposite side walls of the lower water pan 21 near each end thereof. These heaters are supplied with electric currents by means of conductors 31 and 32. Owing to their elongated character and to the fact that they extend approximately tangentially to the rotary heater and at right angles to the plane through which the shaft of 100 105 110

said heater extends, an effective transference of the heat is secured.

Each end of the lower water pan 21 is provided with a standard 35 and between and upon these standards is supported the driving shaft 36 of a rotary fan or blower 37. To said shaft 36 of the blower are secured, between said standards 35 the heads 40, said heads being spaced apart a suitable distance longitudinally of said shaft 36. Said heads carry between them the elongated auxiliary fan blades 41 upon the central portions of which are formed the set of annular plates 44 which are equally spaced apart from each other as shown. Said annular plates 44 are of greater external diameter than the portions of the fan construction at each side of them, and are mounted upon the hub portion 46 of the rotary structure by means of radially extending blades 47 four of which are illustrated. Between these blades 47, webs 48 connect the annular discs as shown, said webs constituting additional fan elements which increase the action of the fan upon the air.

The rotary structure consists of the heads 40, auxiliary plates 41, annular plates 44 and webs 48 which may all be formed as a single casting if desired, but the invention is not limited to thus constructing the rotary structure which produces the air currents within the cabinet.

Describing now more fully the means for guiding and controlling the air currents within the cabinet, to produce the required change of air, air is drawn in through the two small vertical intake tubes 50 one of which is located near each side of the cabinet preferably at the mid-length thereof.

The tubes 50 lead from the top of the cabinet down to a point spaced somewhat away from the floor thereof, preferably a little above the level of the space occupied by the previously mentioned blower. Small outlet air vents 53 are also provided, said vents being preferably located at about the mid-width of the cabinet and at a distance from the ends thereof as shown in Fig. 3.

The bottom water pan 21 extends transversely across the floor of the cabinet along the mid-width thereof, a wide space being left between each end wall of the cabinet and the adjacent side of said water pan. The upper water pan 20 is larger than the water pan 21 and preferably extends the complete length of the unit as well shown, a clear air space 25 being left between each long side of said water pan and the adjacent wall of the cabinet. On the floor of said cabinet at each side of the lower water pan 21, a flue or air guide 57 is provided which leads from the central portion of said water pan diagonally out to a corner portion of the cabinet, said flues or guides are each formed by and between the short strips or plates 59 at one side and the angular plates 60 at the other side thereof. This arrangement is duplicated at each side of the lower water pan 21, it being understood that these flues are confined to the space between the lower pan 21 and the upper water pan 20.

At one end of each cabinet, at both corners thereof, flues 63 are provided to direct the air upwardly. The lower portion of each of said flues is walled off at one side by the vertical plate or wall member 64 above which the flue wall is continued by means of a plate 65x which is inclined toward the opposite end of the cabinet. At the other end of flue 63 the upper portion thereof is provided with a plate or wall member 66 which is likewise inclined to extend parallel with said plate 65x.

The flue construction just described spreads out the ascending air over one side portion of

the cabinet chamber thus securing the general and uniform air circulation desired. The air is caused to descend in an even manner over and through the egg trays leaving no inert space in any part of the cabinet, the course of the air currents being indicated by arrows in all the main views of the drawings.

Describing briefly the electrical connections, current is supplied from the feed wires 70 and 71. The feed wire 70 is provided with a branch 72 which passes through the switch box 73 and supplies current to the motor M, while the line wire 71 is provided with a branch 74 which also passes through the switch box 73, said branch 74 completing the circuit through the motor. The line wire 70 is provided with a branch 75 which, in conjunction with the conductors 31 and 32 completes a circuit through the heaters. The thermostat 65 is included in the latter circuit and automatically maintains the proper temperature within the incubator.

It will be seen that the circuits described will keep the motor M running continuously but will permit the thermostat 85 to interrupt the current as frequently as may be necessary to keep the heat within the cabinet down to the proper degree for incubating the eggs. 65 designates the circuit intercepting structure which is operated by the thermostat 85.

In order that a plurality of units 7 may be operated by a single motor M, a series of the shafts 36 are aligned with each other and coupled together at their ends by coupling devices 36a. By placing these cabinets in a row in contact with each other space is conserved and also the heat generated is economized.

As conventionally shown in the upper portion of Fig. 1, the incubator is provided with a thermostat 85 and a thermometer 86. A glass covered peep hole 87 is also shown in the upper portion 115 of the casing.

The fan or blower 37, from the viewpoint of Figs. 3 and 4, moves the air to the left hand corners of the casing then up between the parts 15, 65x, 66 and the walls, then downward through the trays then downward and outward to the right hand corners (in Fig. 3) and then back to the fan.

What is claimed:

1. In an incubator, a cabinet, a moisture pan within the space enclosed by said cabinet, a series of egg trays positioned within the space enclosed by said cabinet above said moisture pan, a rotary blower, means carried by said moisture pan to support said blower thereabove, an electric heating element also mounted upon said moisture pan, said heating element being supported by side walls of said pan, said heating element being located between said pan and said blower, and means to rotate said blower about a horizontal axis above said pan, said heating element comprising resistance bars which extend at substantially right angles to the plane of the axis of rotation of said blower.

2. In an incubator, a substantially rectangular cabinet having upstanding side walls, a plurality of superposed egg trays mounted within said cabinet, an electric blower mounted upon the central portion of the floor of said cabinet, a pair of air inlet guides constructed and arranged to conduct air from the corner portions of one side of the cabinet to points adjacent to said blower, diagonal air guides at the other side of the blower to conduct the air from the blower to corner portions of the cabinet adjacent the

floor thereof, and means to rotate said blower to entrain air through the first recited air guides and to create air currents outwardly from the central floor portion of the cabinet between the 5 last recited air guides, thence upwardly and back to the first recited air guides.

3. In an incubator, a cabinet substantially rectangular in plan and having vertical walls, a series of superposed egg trays mounted in said 10 cabinet, an electric rotary blower mounted in said cabinet beneath said egg trays, air inlets to conduct the air into the lower portion of said cabinet, said blower being mounted upon a substantially horizontal shaft and being rotatable 15 in a direction to propel the air from said inlets and from one wall of the cabinet toward the opposite wall thereof, and air flues to cause the air currents created by said blower to diverge towards the opposite corners of said cabinet as 20 they leave said blower, the upper portion of said air flues being deflected from the vertical in or-

der to direct the air from said flues toward the interior of the cabinet.

4. In an incubator, a cabinet, a series of superposed egg trays mounted in said cabinet, a rotary blower positioned to circulate air through 80 said egg trays and having a substantially horizontal axis of rotation, an electrically operated heat producing element adjacent to the lower side of said blower, said heating element consisting of elongated resistance elements which extend approximately tangentially of the rotary blower, and an open-topped moisture pan upon which 85 said resistance elements are supported, there being a relatively large air space at the lower side of the blower and a more restricted air space 90 at the upper side thereof and above the path traversed by the rotary elements of said blower whereby a greater volume of air is entrained through said relatively large space than passes 95 the blower through said restricted space.
